(57) **CLAIM**

The ornamental design for the stackable cookware, as shown and described.

DESCRIPTION

FIG. 1 is a perspective view of a first embodiment of the stackable cookware showing the new design;

FIG. 2 is a left-side view of the stackable cookware shown in FIG. 1;

FIG. 3 is a right-side view of the stackable cookware shown in FIG. 1;

FIG. 4 is a front view of the stackable cookware shown in FIG. 1;

FIG. 5 is a rear view of the stackable cookware shown in FIG. 1;

FIG. 6 is a top view of the stackable cookware shown in FIG. 1;

FIG. 7 is a bottom view of the stackable cookware shown in FIG. 1;

FIG. 8 is a front cross-sectional view of the stackable cookware taken along line 8-8 of FIG. 6;

FIG. 9 is a perspective view of a second embodiment of the stackable cookware showing the new design;

FIG. 10 is a left-side view of the stackable cookware shown in FIG. 9;

FIG. 11 is a right-side view of the stackable cookware shown in FIG. 9;

FIG. 12 is a front view of the stackable cookware shown in FIG. 9;

FIG. 13 is a rear view of the stackable cookware shown in FIG. 9;

FIG. 14 is a top view of the stackable cookware shown in FIG. 9;

FIG. 15 is a bottom view of the stackable cookware shown in FIG. 9; and,

FIG. 16 is a front cross-sectional view of the stackable cookware taken along line 16-16 of FIG. 14.
